BLOUSE DISPLAY STAND

Brashier Temple Barnard, P.O. Box 9007,
Greensboro, N.C.

Filed July 30, 1959, Ser. No. 57,001

Term of patent 14 years

(Cl. D80—9)

FIG. 1 is a perspective view of a blouse display stand embodying my new design, a number of the blouse supports being omitted for convenience of illustration;

FIG. 2 is a top plan view thereof; and

FIG. 3 is a fragmentary elevational view thereof, illustrating one of the swinging wire elements in detail.

The blouses shown in broken lines are for illustrative purposes only.

What I claim is:

The ornamental design for a blouse display stand, as shown and described.
